UNITED STATES PATENT OFFICE.

WILLIAM P. HAMMOND, OF CHARLESTOWN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

RACK.

1,099,849.

Specification of Letters Patent. Patented June 9, 1914.

Application filed November 13, 1912. Serial No. 731,106.

To all whom it may concern:

Be it known that I, WILLIAM P. HAMMOND, a citizen of the United States, and a resident of Charlestown, in the county of 5 Suffolk and State of Massachusetts, have invented an Improvement in Racks, of which the following description, in connection with the accompanying drawings, is a specification, like characters on the drawings representing like parts.

This invention relates to racks, and more particularly to shoe racks such as are used in shoe factories for receiving and conveying the shoes from place to place in the factories during the process of the manufacture of the shoes. Heretofore, so far as I am aware, the racks employed for this purpose have been of a permanent construction or non-collapsible. As a result, when stored 20 and not in use they take up a great deal of space. Also the racks have been made of wood, which on account of the harsh usage to which they are subjected, quickly become battered, crippled and so disabled as to render them ineffective for use.

Among other objects, the invention provides a strong, durable rack which may be readily folded or collapsed and set up in readiness for use as desired.

30 The character of the invention may be best understood by reference to the following description of an illustrative embodiment thereof shown in the accompanying drawing, wherein:

35 Figure 1 is a side elevation of an illustrative shoe rack shown therein as embodying the invention; Fig. 2 is an end elevation of Fig. 1; Fig. 3 is a plan view of Fig. 1; Fig. 4 is a view showing the end frames in 40 the process of being collapsed; and Fig. 5 shows the end frames in collapsed position.

Referring to the drawing, the illustrative rack there shown as embodying the invention comprises a base frame 1 including 45 longitudinal side bars 3 conveniently of angle iron. Mounted on the base frame are uprights or end frames 5, each comprising bars 7 preferably of angle iron connected by angle iron cross bars or brackets 9 riveted to said upright angle iron bars 7. Preferably the cross bars extend to and engage the inner faces of the side legs of the upright angle bars and thereby tend to stay 50 and prevent distortion of the end frames.

To further stay the uprights 7, cross bars 55 11 may be provided adjacent the lower ends of the frame and be riveted or otherwise secured to the angle iron uprights. To provide a handle for each end frame and further stiffen the same, a tube 13 of steel or other suitable material may be connected to the upright angle bars 7 at the upper ends thereof. To provide a strong, rigid connection of these handle tubes with said end bars the opposite ends of the tubes may be slotted 65 to receive the opposed inwardly projecting legs of the upright angle bars 7. The tubes are secured to said legs by bolts or rivets projecting through the same. Preferably the tubes 13 do not extend to the inner faces 70 of the outside legs of the angle bars, but are spaced somewhat therefrom to permit the introduction of the upper tray to the uprights as more fully hereinafter described.

75 To permit the uprights to be rocked to and from collapsed and extended positions they may be provided with pivotal connections with the base frame 1. The end frame 5 at the left of Fig. 1 is pivotally connected 80 to the base frame side bars 3 by pins 15 so placed that when the upright frame is rocked to its vertical position shoulders 17 thereof will engage the side bars 3 and prevent further rocking of said end frame 85 in a contra-clockwise direction. The end frame at the right of Fig. 1 is not directly pivoted to the base frame 1, but to permit a proper superposition of the frames, brackets 19 are riveted to the base frame and project upwardly therefrom, the upright end frame being pivoted thereto by pins 21. The lower end 23 of the end frame when the latter is in an upright position abuts 90 against the top of the base frame side members 3 and limits the rocking of said frame 95 in a clockwise direction.

To assist in supporting the end frames in their upright positions, braces 25 are provided having their lower ends conveniently pivoted to the inner faces of the vertical legs of the side members 3 of the base frame. Their upper ends are provided with pins 27 having heads for entrance through key hole slots 29 in the uprights 100 of the end frames. These heads may readily enter said key holes and the shanks of the pins pass into the narrowed ends of the

key holes as the uprights are rocked to positions substantially perpendicular with the base frame. When in these positions it is impossible to further rock the upright end frames in the directions of their extension.

To permit the left end frame (Fig. 1) to rock down to and between the base frame side members 3 without interference from the braces thereof, spacing plates 25^a may be interposed between the uprights 7 and members 3 at their points of pivotal connection.

To permit the rack described to be readily moved from place to place the base frame may be provided with appropriate wheels typified herein as casters 30.

The racks may be provided with suitable shelves to support the shoes, said shelves being preferably of wood so as to prevent any injury to the shoes. These shelves may be of varying form and construction, depending on their use. An illustrative shelf is shown herein comprising side bars 31 connected by end bars 33 and having a bottom 25 formed of cross rods 35. To divide the shelf into pockets for receiving the shoes, partitions 37 may be provided and be slid in grooves in the inner faces of the side bars 31. By this arrangement the partitions 37 may be readily removed when it is desired to provide an uninterrupted shelf or they may be readily inserted to divide the shelf into pockets as desired. As shown herein, four shelves are provided, supported 30 on the brackets 9 in the end frames.

To prevent any possibility of the spreading of the end frames from their proper upright positions and to further stiffen the frame, hooks 39 may be provided conveniently entered through the handle tubes 13. These may be readily rotated to clasp the cross bars 33 of the top shelf and effectively lock the shelf to the upright end frames, or they may be rotated to release the shelf as 45 desired.

The braces may be arranged to hold the end frames slightly inclined toward one another and the latter may have sufficient inherent resilience so that they will need to be sprung apart to permit the introduction of the shelves between them. As a result they will tend to press tightly against and grip the shelves and provide a structure firm and rigid as a whole.

When it is desired to use the rack the end frames 5 may be rocked from their positions shown in Fig. 5 to their positions shown in Fig. 1. The braces 25 are then swung up from the base frame and the heads of the pins 27 entered into the key slots and pressed down into the narrow necks of the key holes. The shelves may then be placed on the brackets 9 and the hooks 39 adjusted to lock the top shelf to the end frames.

When it is desired to collapse the frame

the hooks 39 are released, the shelves removed from the end frames, the braces released from the key holes and rocked down to overlie the side bars of the base frame as shown in Figs. 4 and 5. The left end frame 5 (Fig. 1) is then rocked in a clockwise direction down inside of the base frame and the right hand end frame 5 (Fig. 1) is then rocked in a contra-clockwise direction, as shown in Fig. 4, down to overlie the left hand end frame and base frame, as shown in Fig. 5. The frames are then in collapsed relation and form a very compact structure. When in this condition the racks may be piled away and stored and occupy but little 80 space.

By my invention is provided a shoe rack which is extremely simple in construction, cheap to manufacture, strong and durable and one which may be quickly readily set up 85 or collapsed as desired.

Heretofore the non-folding rack employed had to be manufactured near the place of its use in order to avoid the large cost which would be necessary in shipping such a bulky 90 structure. The rack described herein occupies such little space that it may be readily made at points remote from the place of its use and be shipped with slight expense.

Having described one embodiment of my 95 invention without limiting the same thereto, what I claim as new and desire to secure by Letters Patent is:

1. A foldable shoe rack comprising in combination, a horizontal base frame, upright resilient bars pivotally connected to the end of said base frame, shelf supporting cross members distributed at intervals along said upright bars, shelves removably supported on said cross members and having ends engaging the inner faces of the upright bars and braces pivotally connected to said base frame and having provisions for detachably engaging said upright bars and for pressing the inner faces thereof 110 against the ends of the shelves.

2. A foldable shoe rack comprising in combination, a horizontal base frame, upright resilient bars pivotally connected to the ends of said base frame, shelf-supporting cross members distributed at intervals along said upright bars, shelves removably supported upon said cross members, and detachably interengageable hook members upon an upper shelf and said upright bars 120 to draw the latter toward each other and thereby to hold the parts rigidly in position.

3. A foldable shoe rack comprising in combination, a horizontal base frame, upright resilient bars pivotally connected to the ends of said base frame, shelf supporting cross members distributed at intervals along said upright bars, shelves removably supported upon said cross members and means engaging the upright bars near their 130

lower ends to spring them toward each other.

4. A foldable shoe rack comprising in combination, a horizontal base frame, upright resilient bars pivotally connected to the ends of said base frame, shelf-supporting cross members distributed at intervals along said upright bars, shelves removably supported upon said cross members, means engaging the upright bars adjacent to but spaced from their lower ends, and consti-

tuting supports with respect to which the bars may be sprung, and means engaging the upper portions of said bars to hold them in sprung position.

15

In testimony whereof, I have signed my name to this specification, in the presence of two subscribing witnesses.

WILLIAM P. HAMMOND.
